UNITED STATES PATENT OFFICE

THEODORE E. MUELLER, OF LOUISVILLE, KENTUCKY, ASSIGNOR TO STANDARD SANITARY MANUFACTURING COMPANY, OF PITTSBURGH, PENNSYLVANIA, A CORPORATION OF NEW JERSEY

DESIGN FOR A SINK

Application filed February 10, 1932. Serial No. 42,802. Term of patent 14 years.

To all whom it may concern:

Be it known that I, THEODORE E. MUELLER, a citizen of the United States, residing at Louisville, Jefferson County, in the State of Kentucky, have invented a new, original, and ornamental Design for a Sink, of which the following is a specification, reference being had to the accompanying drawing forming a part thereof.

In the drawing—

Figure 1 is a perspective view showing a sink embodying my said design;

Fig. 2 is a front view thereof, and

Fig. 3 is a section on the line 3—3 of Fig. 2.

I claim:

The ornamental design for a sink, as shown.

THEODORE E. MUELLER.
